UNITED STATES PATENT OFFICE.

FRED S. MORTON, OF WORCESTER, MASSACHUSETTS, ASSIGNOR TO MATTHEWS MANUFACTURING COMPANY, OF WORCESTER, MASSACHUSETTS, A CORPORATION OF MASSACHUSETTS.

ROLLER.

1,137,781.

Specification of Letters Patent. Patented May 4, 1915.

Application filed October 22, 1914. Serial No. 868,114.

To all whom it may concern:

Be it known that I, FRED S. MORTON, a citizen of the United States, residing at Worcester, in the county of Worcester and 5 State of Massachusetts, have invented a new and useful Roller, of which the following is a specification.

This invention relates to rollers and particularly to a roller adapted for use on ball 10 bearing roller skates.

This invention is designed as an improvement on the type of roller shown in Letters-Patent No. 1,021,362, granted March 26, 1912, to Otis W. Everett and has for its object to improve the construction of rollers 15 of this type while at the same time reducing the number of parts and providing for cheapness of manufacture.

The accompanying drawing shows a perspective view partly in section of a preferred form of my invention.

My improved skate roller consists essentially of three parts, a tread portion 10 having integral therewith a side member 11, a 25 ball cup 12 and a second side member 13. The usual balls are indicated at 14 and the roller is shown as mounted upon a grooved shaft 15, the balls and the shaft having no novel features and constituting no part of 30 my invention.

The ball cup 12 has a circumferential bearing surface 16 and a side flange 17, these parts constituting two sides of the ball race. The ball cup has also a peripheral projection 18 which serves to position the cup within the side member 11 and to prevent its displacement therefrom in one direction.

The side member 13 may have a circumferential inturned flange 19 and is secured within the tread 10 by frictional contact. The edge of the tread 10 may, if desired, be headed over on the inside as indicated in the drawing to form an additional securing 45 means for the side member 13. This side member is extended inwardly nearly to the shaft 15 and serves two purposes, first, to prevent movement of the ball cup 12 toward the left (as viewed in the drawing), and 50 second, to constitute the third side of the ball race.

It will thus be seen that I have provided

a skate roller involving in its construction only three parts and that each of these parts is simple in form and may be readily made 55 from pressed sheet metal. The economy in manufacture resulting from this simple construction is apparent.

While I have described my invention as applicable to a skate roller, its construction 60 is such that it is equally well adapted for other purposes and such use is contemplated in this application.

It will be obvious that many changes and modifications can be made in my invention 65 as herein disclosed without departing from the spirit and scope thereof and I do not wish to be limited to the specific details herein shown, but

What I do claim is:

1. A roller comprising a tread, a side member secured thereto, a ball cup secured in said side member and forming two sides of a ball race, and a second side member mounted in the tread and forming the third 70 side of the ball race.

2. A roller comprising two side members, a tread, and a ball cup, said cup having a circumferential bearing surface and one side flange and being secured within one of the 75 side members, and the other side member extending inwardly and forming a second side flange which completes the ball race.

3. A roller comprising two side members, a tread, and a ball cup, said cup being secured in one side member, said tread being integral with the same member, and the other side member being secured within the tread, the inner portion of said second side member being effective to close one side of 90 the ball cup and to retain the balls therein.

4. A roller having a unitary tread and side member, a ball cup mounted in said member and having a peripheral projection which prevents movement of the cup relative to the member in one direction, and a second side member secured within the tread and effective to prevent movement of the cup in the opposite direction.

5. A roller having a unitary tread and side member, a ball cup mounted in said member and having a peripheral projection which prevents movement of the cup relative to the member in one direction and a

second side member secured within a tread and effective to prevent movement of the cup in the opposite direction, the inner portion of the last named side member constituting one side of the ball race.

6. A roller comprising a tread, a side member, a ball cup mounted in said side member, and a second side member retaining said cup in position in the first named

side member and constituting a closure for one side of the ball cup.

In testimony whereof I have hereunto set my hand, in the presence of two subscribing witnesses.

FRED S. MORTON.
